BOWL CONTROL FOR CARRY TYPE
SCRAPERS

Leland T. McGee, Los Angeles, Calif.

Application February 28, 1947, Serial No. 731,625

5 Claims. (Cl. 37—129)

1

My invention relates to dirt scrapers, and particularly to dirt scrapers of the type usually operated by power tractors, and which are capable of scraping up a load of dirt, hauling it a distance, as pulled by said tractor, dumping it at the will of the operator of said tractor, and also spreading said dirt as it is dumped over an area at different depths by adjusting the scraper bowl upwardly in its dumping position, and of being returned again to the scraping and loading position, and all controlled by the operator of the tractor by a single, manually manipulated control lever, in a single fluid line, whereby hydraulic fluid is directed into rams where it can be locked or released at will to move or to hold, or to release said scraper.

Among the salient objects of my invention, in addition to the above-mentioned functions and advantages are: To provide a dirt scraper of the type referred to in which there is a movably supported bowl, with a plurality of supporting and moving levers, pivotally connected therewith, at different points on the opposite sides of said bowl, whereby said bowl can be bodily moved from loading to carrying, or dumping positions, while at the same time being pivotally held and operated by said levers by means of hydraulic power applied to said levers; to provide in a dirt scraper of the character referred to hydraulic power means for positively moving said supporting and operating levers and said bowl in one direction, while permitting gravity to return said levers and said bowl to the different intermediate positions; to provide in connection therewith an automatically controlled valve mechanism which is operated by the movement of the scraper bowl, said bowl and said valve mechanism being connected and timed to work together.

Other advantages of the invention will appear from the following detailed description of one practical embodiment thereof shown on the accompanying four sheets of drawings, in which:

Figure 1 is a plan view of a dirt scraper embodying my invention, looking down into the bowl, and showing the rear end of a tractor, and showing the rear end of the scraper frame and wheels broken away to reduce the size of the figure;

Figure 2 is a side elevation of the invention showing the scraper bowl in the digging or loading position;

Figure 3 is a similar view showing the bowl raised to the carrying position;

Figure 4 is a similar view showing the scraper bowl in the dumping position and being held for spreading the dirt in a thin layer over an area;

Figure 5 is a similar view showing the scraper bowl raised a little higher than the position shown in Fig. 4, for spreading the dirt in a thicker layer over an area;

Figure 6 is a similar view showing the scraper bowl raised to its upper limit and from which it can be lowered again to the digging or loading position, as shown in Fig. 2;

2

Figure 7 is a fragmentary view of the mechanism shown in Fig. 4, showing the opposite side thereof to show the pipe connections;

Figures 8, 9 and 10 are vertical sectional views all taken on the line 8—8 on Fig. 1, showing different positions of the valve in the hydraulic control mechanism;

Figure 11 is a fragmentary sectional view taken on the line 11—11 through the top of Fig. 8;

Fig. 12 is a sectional view taken on line 12—12, Fig. 2;

Fig. 13 is a sectional view taken on line 13—13, Fig. 2;

Fig. 14 is a sectional view taken on line 14—14, Fig. 2;

Fig. 15 is a sectional view taken on line 15—15, Fig. 6;

Fig. 16 is a sectional view taken on line 16—16, Fig. 6; and

Fig. 17 is a sectional view taken on line 17—17, Fig. 16.

Referring now in detail to the drawings, Figs. 1 and 2, a scraper frame is shown, including two side members 20, 20, connected at their forward ends by a cross member 21, shown in tubular form, and having an upstanding, rigid A-frame structure 22, for coupling purposes, said frame being shown in Figs. 1, 2 and 14, and having a forwardly extending arm 23, from its upper end, which arm is of tubular form and is provided in its end with a telescoping member 24, seen in Fig. 12, having a bail and socket joint at 25 for coupling purposes, also seen in Fig. 2, for coupling the scraper frame to a tractor, the rear end of which is shown in said Figs. 1 and 2. Said frame sides, 20, 20, toward their rearward ends are connected by a second cross member 26, from which extend two members 27, 27, parallel with the ends of said side members, to form therewith supports for two carrying wheels, 28, 28, as clearly indicated in Fig. 1.

At the forward end of said frame and the cross member 21, in the middle of the latter, is a downwardly depending member 29, bifurcated at its lower end, to which is connected one end of a coupling rod 30, as seen in Fig. 3, while the forward end of said coupling rod is connected in the same manner with a depending member 31, on the rear of the tractor, as seen in Fig. 2, and shown in section in Fig. 13. Thus by means of the members 22, 23, and the rod 30, the scraper frame is capable of being coupled to a power tractor, as illustrated in said Figs. 1 and 2.

Mounted upon the side members 20, 20, and rigid therewith, are two pairs of upstanding supporting brackets 32, 32, and 33, 33, of different heights, as will be seen in Figs. 2 and 3. These support the pivoted ends of two pairs of arms or levers, 34, 34, and 35, 35, which arms or levers are pivotally connected at their free ends with a scraper bowl B. The arms or levers 34, 34, are pivotally connected with the bowl B at its lower, forward, opposite sides, as at 34', 34', and at

their upper ends, said levers are slotted, as at 33, and are pivotally and slidably connected with the forward supporting brackets 32, 32, as clearly indicated in the side views. The arms or levers 35, 35, are pivotally connected at their free ends with the opposite sides of said bowl B, as at 35', 35', and at their opposite ends said levers 35, 35, are pivotally connected with the upper ends of the rearward supporting brackets 33, 33, by means of a cross rod 37, to which said arms are rigidly connected, and as seen in Fig. 1, one end of said rod 37, carrying thereon, outside of the supporting bracket 33, a depending plate 38, Figs. 8, 9 and 10, having therein a slot 38' operating over a pin or stud 39, in the end of said rod 37. The ends of said cross rod 37 have collars, as 37', welded or otherwise secured thereto, with a bushing 40 within the supporting bracket 33, as indicated in Fig. 11.

Pivotedly connected to the opposite sides of the front of the scraper bowl B, by the arms 41, 41, is an apron 42, having connected therewith a chain 43, the upper end of which is adjustably connected to the upper end of the A-frame 22, as indicated at 44, on a finger.

Said pivoted apron is adjusted to different positions relative to the open front of the scraper bowl by the movement of the bowl, as will be understood by the different positions thereof in Figs. 2 to 6 inclusive, being held above the opening into the bowl in loading position, as in Fig. 2, while closing said opening to the bowl in the carrying position, as seen in Fig. 3, and being held out of the way in the loading, unloading and leveling positions, as in Figs. 4 and 5.

I will now describe the hydraulic mechanism by which said bowl is moved to the different positions indicated in Figs. 2 to 6 inclusive.

Two cylinders, as 45, are connected pivotally with the two arms or levers 35, 35, at opposite sides of the bowl, intermediate the ends of said levers, as at 46, said cylinders or tubes 45 having telescoping therein tubes as 47, the outer ends of which are connected, as at 48, with a supply pipe 49, leading through the side member 20, along said side member 20, to the forward end of the frame into the cross member 21 and up to the upper end of the A-frame 22, as seen in Fig. 14, where it is connected with the flexible tube 50, from the supply pump on the tractor. This pump is standard equipment on tractors of this character and it has a valve control mechanism, as at 51, for controlling the flow of hydraulic fluid to the tube 50, and thence through pipe 49, as will be understood. It will be understood also that the supply pipe 49, extending rearwardly along the side member 20, as seen in Figs. 4, 5 and 6, also extends through said member 20, and across to the other side, as at 49', for connection with the other tube 47, operating the other cylinder or tube 45, for simultaneous operation of these members on the arms or levers 35, 35. By reference to Fig. 16, we have shown these telescoping tubes 45 and 47 in enlarged sectional view. From the pivot head 52, pivoted at 52', supported in a depending bracket 53, one at each side of the frame, are two connecting straps as 54, 54, rigid with said pivot head, and at their opposite ends having a ring 55, around the end of the outer cylinder or tube 45, as seen in Fig. 16, to act as a stop for the tube 45, as it is forced outwardly on the inner tube 47, said tube 45 having a shoulder at 45' for this purpose. For clearness, these straps 54, 54 are not shown in the assembled showing in Figs. 1-6.

Thus it will be seen that the hydraulic fluid forced through the tube 50, pipes 49 and 49', to the connections at 48, at opposite sides of the frame, will operate to force the cylinder or tube 45, on each side of the frame, upwardly, and as these are connected with the levers 35, 35, which are connected with the opposite sides of the bowl, as at 35', said bowl will be moved from the position shown in Fig. 2, to the position shown in Fig. 3, the other end of said bowl being also forced to its position in Fig. 3, by the other pair of cylinders, now to be described.

Connected with the levers 34, 34, intermediate their ends, as at 55', are plungers 56, operating in cylinders, as 57, pivotally connected and supported in depending brackets, as 58, on the undersides of the side members 20, 20, as seen in Figs. 2 to 6, inclusive.

Said plunger and cylinder are shown in sectional view in Fig. 15, and the mountings or connections are similar to the connections in Fig. 16, except in the structure shown in Fig. 15, there is a plunger rod 56 operating in the cylinder or tube 57, instead of an outer tube or cylinder moving over the inner tube, as shown. The pivot head 59, in the bracket 58, is connected rigidly with the cylinder or tube 57, as indicated and pivotal movement is permitted at this point, while the plunger rod 56 is connected pivotally with the lever 34, as at 55', and as said plunger rod 56 is forced outwardly it moves said lever 34, and this end of the scraper bowl B therewith from the position shown in Fig. 2, to the position shown in Fig. 3. It will be understood that this mechanism is the same on both sides of the scraper bowl.

In Fig. 15, side straps, as 56, 56' are shown connecting the pivot head 55', to which they are welded, to a stop ring 57' around the tube 57. These straps are not shown in Figs. 1-6.

The hydraulic fluid for operating the plungers and moving the scraper bowl to its various positions is supplied from the pump mechanism on the tractor, standard equipment, and is controlled by the valve mechanism thereon, designated 51, Fig. 2. This fluid is directed through the tube 50 to the pipe 49, extended along the side of the frame member 20 and at the rearward end thereof, inserted through said side member 20 and extended across said frame to the opposite side, as seen in Fig. 1, with the extensions, as 49, 49', to connect it with the two cylinders or tubes 47, 47, as at 48.

Thus it will be noted that a single oil or hydraulic fluid line from the tractor controls all of the movements necessary in operating the scraper. By the single valve 51, on the tractor pump, the hydraulic fluid is forced into the different rams or cylinders, or is locked therein, or is released to return from the rams or cylinders to the pump. In other words, by a single control valve, the operating fluid can be directed into the rams or cylinders which positively move the levers supporting the scraper bowl and thereby move the bowl into its different positions, and when said bowl has been moved to its unloading and spreading position, it must complete its cycle of movement in order to return to a digging or loading position. The scraper bowl can be moved up and down for various cuts in loading, or up and down for different heights for spreading, but once in the spreading position, it must complete its cycle in order to return by gravity to a digging or loading position.

From the pipe 49, from the pump or control valve 51, is a branch pipe 60 extended to and

connected with a valve box 61, as seen in Figs. 8, 9 and 10, through which fluid is directed, controlled by a ball valve 62, moved by a spring 62', and which fluid is directed out through a pipe 63, to tube 64, by which it is connected with the tube or cylinder 57, pivotally supported in the bracket 58, with a coupling head 59, as shown. The pipe 63 from the valve box 61, at the side of the frame 20, has an extension 63' extended through said side member 20 and across to the opposite side of the frame structure for connection with the cylinder or tube 57 at the opposite side of the scraper bowl E, in the same manner as indicated in Fig. 7, a fragmentary portion of the opposite side of the machine at this location, where said extension 63' is shown connected to a tube 64' which is connected with the cylinder or tube 57 on the opposite side of the machine, as shown.

The valve 62 in the valve box 61 has a stem, shown in Figs. 8, 9 and 10, with its end positioned to be engaged and depressed by the lower end of the plate or member 38, on the end of the cross shaft 37, which has the arms or levers 35, 35, secured thereto, whereby said shaft 37 is turned by said arms as they are moved to move the scraper bowl, by the plungers 45-47, before described.

Thus it will be understood that the movement of the scraper bowl by the arms 35, 35, which are secured to said shaft 37, operates said plate or member 38 to open said ball valve 62 against the tension of its spring 62'. Said member 38 is moved by the pin or stud 39 in the end of said shaft 37, as seen in Fig. 10. In Fig. 8 the valve is open and the pressure in pipes 60 and 63 and in said valve box 61 is equalized, if turned on at the control valve 51 on the pumping mechanism on the tractor, or, if said control valve is set at neutral, the oil or hydraulic fluid is locked and there is no bowl movement. If the valve 51 is moved to its opposite extreme, said hydraulic fluid can be forced back through said valve by the gravity movement of the bowl and its connections to the plungers and the cylinders or tubes which operate to move said bowl. The weight of the scraper bowl and levers causes the return of the hydraulic fluid to the pump or reservoir therefor, allowing the scraper bowl to move by gravity to the position in Fig. 2. In other words, it will be understood that the two ends of the scraper bowl are moved by the plungers 45 for the rearward end, through levers 35, 35, and plungers 56, 56, for the forward end, through levers 34, 34, at the opposite sides of the scraper bowl as hydraulic fluid is admitted by the control valve 51 to said plungers. After the scraper bowl has moved by gravity to its down position, shown in Fig. 2, control valve lever 51 is then moved to the neutral position to prevent further downward movement.

There is also provided in said valve box mechanism, shown in Figs. 8, 9 and 10, a safety-valve box 65, connected at its opposite sides with the supply pipes 60 and 63, with a valve 66, normally held closed by a spring 67. This operates automatically should pressure become too great in cylinders or tubes 57, 57, when the scraper bowl is in the dumping and leveling or spreading positions, as shown in Figs. 4 and 5. The pressure then would escape through the safety valve 66 into the other pipe 60.

Thus I have provided in connection with a power scraper of the character shown and described, power means connected with supporting levers, and have shown how the scraper bowl

can be moved into the different operating positions by applying power to the supporting levers for said bowl, said power being applied to said levers intermediate their ends, thus functioning after a lever of the third class or order. As the power is applied to the levers in pairs, the scraper bowl is moved at its opposite ends, one pair of levers operating on the rearward end of the scraper bowl, and another pair of levers operating at opposite sides of said bowl at its forward end. The scraper bowl returns to its down position by gravity when the power is released, as hereinbefore described. The different positions of the scraper bowl are illustrated in the different views, as described.

Use and operation

The use and operation of the invention may be briefly described as follows:

Referring to Fig. 2, the control valve 51, on the tractor, is shown in the neutral position, which locks the oil in the pipes and cylinders and prevents its being returned to the reservoir from which it was pumped. Said control lever was moved to this neutral position after the scraper bowl had been allowed to move by gravity into this down or loading position while said lever 51 was in its forward or releasing position.

Referring also to Fig. 8, the valve 62 is also shown held in its open position by the plate 38, which is on the shaft 37, and turned by said scraper bowl, as it moves. This position of said valve 62 permits the oil to flow freely between pipes 60 and 63 as said bowl moves by gravity to the position shown in Fig. 2.

In Fig. 2, assuming that the scraper bowl is loaded and it is desired to move it to the carrying position shown in Fig. 3, this is accomplished by moving the control lever 51 backwardly to the operating or pumping position. This forces oil through the line 50 to the cylinders 57 and 45, connected with the supporting levers 34 and 35 of the bowl, thus raising said scraper bowl to the carrying position, as shown in Fig. 3. Also at the same time, the shaft 37, which turns with levers 35, 35 and said bowl as it is moved, has moved its operating pin 39 to the position shown in Fig. 9, which moves the slotted plate 38 to the position shown, ready to release the valve 62, to permit it to be closed by its spring 62', as seen in Fig. 10.

During the carrying position of the scraper bowl, control valve 51 is in a natural or locking position for the fuel line.

When it is desired to dump the load from the scraper bowl, the control valve 51 is moved rearwardly to the operating or pumping position, whereupon oil is again forced through the pipe line 50 to the cylinders 57 and 45, connected with the levers 34 and 35.

During this movement, one pivotal point 35 of lever 35, at the rear of the bowl, is moved above a line from pivot point 34' to the shaft 37, on which the valve operating plate 38 is mounted, then the front end of the bowl falls down, around pivot support 35', to the position shown in Fig. 4, which is a spreading position, as the dirt is being discharged from the bowl in its tilted position. While this is taking place, the oil in the cylinder 57, which is smaller than cylinder 45, is being forced out into the line 60 and into cylinder 45, which results in allowing the bowl to swing to the spreading position shown in Fig. 4. This is the first spreading position, spreading a layer of dirt over the area.

Should it be desired to spread the dirt in a heavier layer, the control lever 51 is moved back into operating or pumping position to open the way for oil to be pumped into cylinder 45, which raises lever 35 and the scraper bowl to a higher position. This is permitted by the slots 36, in the upper ends of levers 34, at opposite sides of the bowl. Cylinders 57, at opposite sides of the machine, in the position shown in Fig. 5, operate as stops to prevent the lower end of the bowl from moving further backward.

In this dumping position, the ball valve 62, Fig. 10, has closed the passageway from line 60 to line 63. This, in a way, makes an automatic regulator in that the oil pressure in line 63 builds up sufficiently to move cylinder 45 to the limit of its stroke. Ball valve 62, being closed, prevents the oil from passing into cylinder 57, until cylinder 45 has reached the limit of its stroke, whereupon the pressure in line 60 rises to a point where it forces said valve 62 open and allows the oil to be forced through line 63 to cylinder 57, and move it to the end of its stroke, which brings the bowl from the dumping position in Fig. 5, to its uppermost position shown in Fig. 6.

When the control lever 51 is moved forwardly to release the oil, the oil is prevented from returning from 57 by the ball valve 62, but is allowed to return from cylinder 45, which permits lever 35, and the end of scraper bowl to lower to the position shown in Fig. 3. At this stage of the operation, the valve mechanism 61, has been operated by shaft 37 and plate 38, to open the valve 62 to permit the oil to flow freely out of both cylinders 57 and 45, and the bowl to move to the position shown in Fig. 2.

By moving the control valve 51 backwardly to the operating or pumping position, oil can be forced through line 50 to the cylinders 57 and 45, and through their lever connections said bowl and its load is raised to the position shown in Fig. 3, which is the carrying position.

Thus with this construction and arrangement, with a single fuel line and a single control valve, said scraper bowl can be moved to the different positions described, and allowed to return by gravity, and while changes in details can be made within the spirit of the invention, I do not limit the invention to the showing made, except as I may be limited by the hereto appended claims.

I claim:

1. In a dirt scraper: a supporting frame with carrier wheels, a scraper bowl pivotally supported in said frame by levers, there being two levers between the opposite sides of said frame and the opposite sides of said scraper bowl toward its rearward end, and two levers between the opposite sides of said frame and the opposite sides of said bowl toward its forward end, power means operatively connected with said first mentioned levers intermediate their pivotally attached ends for moving the rearward end of said bowl, power means operatively connected with said secondly mentioned levers intermediate their pivotally attached ends for moving the forward end of said bowl, and means for controlling the application of said power means to said bowl supporting levers to move and tilt said bowl in its operation.

2. In a dirt scraper, a carrier frame with wheels at its rearward end and hitching means at its forward end, a scraper bowl movably supported in said frame by means of two pairs of pivoted levers between said carrier frame at opposite sides thereof and the opposite sides of said

bowl forwardly and rearwardly thereof, hydraulically operated plungers at opposite sides of said frame with means for controlling the flow of hydraulic fluid thereto, said plungers being operatively connected at their outer ends with said pivoted supporting levers for said scraper bowl, intermediate their pivotally connected ends, for moving said bowl bodily at its opposite ends, said controlling means being releasable to permit said bowl to move downwardly by gravity.

3. In a dirt scraper, a carrier frame having carrier wheels, said frame having supporting standards on its top, spaced forwardly and rearwardly on said frame, a scraper bowl movably supported in said frame, two supporting levers on each side of said bowl, pivotally connected at one end to said supporting standards and at their other ends to the side of said bowl forwardly and rearwardly thereof, two pairs of hydraulic cylinders and plungers, one pair at each side of said bowl, the outer ends of said plungers being pivotally connected with said supporting levers for said bowl, between their pivoted ends, and control valves for controlling hydraulic fluid to said cylinders for moving said levers by the application of power thereto between their pivoted ends.

4. A dirt scraper including a carrier frame with carrier wheels therefor and hitching means for coupling it to a power vehicle, a scraper bowl movably supported in said frame by two pairs of pivoted levers interposed between said frame and the opposite sides of said bowl, hydraulic power means at opposite sides of said bowl in said frame and including two pairs of hydraulically operated plungers, a plunger being connected at its outer end with each pivoted lever, between its pivotally connected ends, pipes for conveying hydraulic fluid to said hydraulic power means from a source of supply, valves interposed in said pipe lines for controlling flow of hydraulic fluid, and means operated by the movement of said scraper bowl for operating one of said valves to release said hydraulic power and permit said scraper bowl to move by gravity to its down position.

5. A dirt scraper including a carrier frame with carrier wheels therefor and hitching means for coupling it to a power tractor, a scraper bowl supported in said frame for bodily movement to different operating positions, said bowl being supported by a pair of levers at each side thereof, said levers being pivotally connected at their anchored ends to the side of said frame, and at their free ends to the sides of said bowl forwardly and rearwardly thereof, hydraulically operated plungers, one for each of said levers, connected therewith between its pivotally connected ends, to apply power thereto after the manner of a lever of the third class, means for controlling the flow of hydraulic fluid to said hydraulically operated plungers, and valve means with operating connections from said scraper bowl for operating one of said valve means by the movement of said scraper bowl to release said hydraulic fluid to permit said scraper bowl to move by gravity to its digging position.
